[57] CLAIM

The ornamental design for table leg, as shown and described.

DESCRIPTION

FIG. 1 is a front perspective view of a table leg, showing my new design, the broken lines are for illustrative purposes only;

FIG. 2 is a side elevational view, the opposite side being a mirror image thereof; and,

FIG. 3 is a rear perspective view thereof.

FIGS. 2 and 3 have been drawn to a reduced scale with respect to FIG. 1.
